UNITED STATES PATENT OFFICE.

EDWARD P. O'BRIEN, OF EAST WEYMOUTH, MASSACHUSETTS.

WOOL-DELIVERING DEVICE.

1,159,259.

Specification of Letters Patent.

Patented Nov. 2, 1915.

Application filed December 15, 1914. Serial No. 877,391.

To all whom it may concern:

Be it known that I, EDWARD P. O'BRIEN, a citizen of the United States, residing at East Weymouth, in the county of Norfolk and State of Massachusetts, have invented 5 new and useful Improvements in Wool-Delivering Devices, of which the following is a specification.

This invention relates to a device for delivering the wool to the feeders of wool scouring machines, and its object is to provide a device whereby an even and regulated supply of wool to the feeder may be secured, thus obviating the known objections 15 to the irregularities of hand feeding while enabling a single attendant to control the supply of wool to a plurality of feeders.

A further object of the invention is to provide a delivery means whereby the wool may 20 be delivered fast or slow according to the character of the wool or running speed or capacity of the feeder, so as to secure a regular and even feed which is essential to the efficient action of the scouring machine.

25 The invention consists of the features of construction, combination and arrangement of parts herein fully described and claimed, reference being had to the accompanying drawings in which:—

30 Figure 1 is a front elevation of a feeder and wool chute, the door of the chute being thrown open, showing the application of the invention thereto. Fig. 2 is a side elevation of the same. Fig. 3 is a front to rear section. Fig. 4 is a sectional plan view on line 4—4 of Fig. 3. Fig. 5 is a fragmentary view looking toward the opposite side of the chute from that shown in Fig. 2, and showing the controlling lever, a portion of 35 the chute being broken away to show the table and reel. Fig. 6 is a fragmentary perspective view of the adjustable feed regulating table. Fig. 7 is a detail section on the line 7—7 of Fig. 2. Fig. 8 is a detail section on line 8—8 of Fig. 5. Fig. 9 is a detail section on the line 9—9 of Fig. 2.

40 Referring to the drawings, 1 designates a wool feeder of known type, which is supplied, as usual, with wool for delivering to the scouring mechanism by means of a chute 2. In modern scouring plants, the scouring machines and feeders are generally arranged

upon the lower floor, and the wool is supplied to the feeders from the floor above through chutes of the character disclosed. 55 Ordinarily an attendant is required for manually delivering the wool contained in the chute to the feeder, great care and exactness in feeding the wool being necessary in order to avoid poor or uneven work, uniform and 60 even feeding being absolutely essential in wool scouring. As a result, through carelessness or inefficiency, a great deal of poor or improper work is done, and an attendant must be employed for supplying each feeder, 65 a source of considerable expense in large plants.

My invention provides a delivery mechanism which overcomes these objections, and which insures absolutely smooth and even 70 feeding of a character suited both to the wool and action of the scouring machine, and which at the same time obviates the necessity of employing an attendant for each feeder and chute, a single attendant being 75 able to take care of a number of feeders operating at the same time.

In carrying my invention into practice, I provide within the chute 2, at a point about in line with the door 3 thereof, an adjustable 80 feed regulating table 4, which table is designed to support the body of wool contained within the chute and comprises an imperforate body portion provided with spaced slats or fingers 5, providing a plurality of spaced intervening feed passages for the downward supply of the wool to the feeder 1. The table is adjustably mounted in the manner hereinafter described.

Journalized in the side walls of the chute 90 2 and extending horizontally across the same below the slatted table 4 is a shaft 6 carrying a series of toothed wheels 7, forming a reel operating beneath the slatted table, and the teeth of the wheels or disks of which are 95 adapted to pass through or work in close contiguity to the slots between the slats 5 and to rake through and draw down particles of the wool exposed therethrough, which are thereby supplied to the feeder 1 100 for conveyance to the scouring machine. By adjusting the table so that the slatted portion thereof will lie closer to or farther from the teeth of the wheel disks it is evident that

the amount of wool taken up or gathered by the disks may be varied according to the speed or scouring capacity of the mill and to the grade or character of wool which is being supplied thereto to be scoured.

5 Intermittent feed mechanism for actuating the reel is provided and comprises a wheel or disk 8 fixed to one end of the shaft 6 and which is provided with a wrist pin 9 to which is coupled one end of a pitman 10, the opposite end of which is coupled to a wrist or crank pin 11 carried by a block 12 slidably engaging a slot 13 in a crank arm 14 projecting from a crank head or disk 15. 10 This head or disk 15 is secured to one end of a horizontal transverse drive shaft 16, which may be driven from any suitable source of power and provided with a drive pulley or gear element of a suitable character for that purpose.

15 The block 12 is adapted to be adjustably secured in position at any point along the length of the slot 13 by suitable fastening means, such as a screw stem 12^a integral 20 with the block, together with a washer 12^b and nut 12^c, the lever 10 being held in engagement with the wrist or crank pin 11 by a cotter pin 11^a. In the rotation of the shaft 16 the crank arm 14 transmits motion to the 25 crank disk 8 through the pitman 10 and crank pin 9, and by adjusting the block 12 and wrist pin 11 along the slot 13 it will be evident that the effective radius and stroke 30 of the crank arm 14 may be varied to correspondingly vary the degree of motion of the 35 rotating disk 8, as will be readily understood. Fulcrumed upon the disk 8, which is loosely mounted on the shaft 6, is a dog or pawl 17 adapted to engage the teeth of a 40 ratchet wheel 18 fixed to the shaft 6, so that on the working motion of the disk 8 the dog will contact with the shoulder of one tooth and move the ratchet wheel, disk and rail a predetermined distance or portion of 45 a revolution while on the return motion of said disk the dog will slide over the inclined faces of the teeth and be reset for a subsequent feed action. The slats or fingers 5 of the table 4 are secured to bracket lugs 19 50 provided with sleeves 20 having angular bores for the passage of a rock shaft 21 and secured to said shaft by screws or other like fastenings 22. The ends of the shaft 21 are fitted in collars 23 journaled in bearings 24 55 in the side walls of the chute. A cotter pin or key 25 passes through one end of the shaft and holds the same against longitudinal displacement, while the other end of the shaft is connected with the upper end of 60 a controlling lever 26, said lever being provided with a longitudinal slot 27 for the passage of the threaded stem 28 of a headed guide and pivot pin 29, the headed end of which is fitted to slide in a slotted guide bracket 30, the parts being held against

relative displacement by a nut or other suitable fastening device 31. The bracket 30 extends in a substantially horizontal plane across one side of the chute, and it will be evident that as the lever 26 is moved forward or backward it will rock the shaft 21 in corresponding directions. The sliding connection between the lever and the pin 29, and between said pin and the guide bracket, adapt the lever to be adjusted to rock the shaft and secure it in adjusted position by tightening the nut 31 to clamp the head of the screw 30 against the slotted wall of the guideway, the screw sliding longitudinally of the lever to compensate for the variations in the arcs of movement of the pivoted portion of the lever and the end thereof connected with the rock shaft. When the table is raised the bulk of the wool resting thereon is held to a greater or less extent out of 85 the path of movement of the teeth of the wheel 7, so that a relatively small amount of wool will be supplied to the feeder, while by lowering the table an extent of projection of the teeth of the wheel 7 through the 90 spaces between the table fingers will be increased, allowing the toothed wheels to draw down a greater amount of wool, so that the supply of the wool to the feeder may be regulated to an exact degree. 95

It will thus be apparent that the operation of the delivery reel may be varied for a complementary action of the table according to the position of the latter and the speed of action of the scouring machine, so that the apparatus may be set as conditions may require to handle any kind of wool according to governing conditions and to deliver wool with a mathematical exact and even regulated rate of speed, so that the exact amount of wool for a proper scouring action and no more will be delivered. As a result greater efficiency of action of the scourer is obtained, while the use of the delivery device obviates the necessity of employing an attendant for each feeder, a single attendant being enabled to handle a number of feeders, with a consequent reduction of expense to the establishment. 110

I claim:—

1. In a delivery mechanism for wool scouring machines, the combination with a wool feeder, and a wool chute, of an adjustably mounted slatted table within said chute, a rotary reel arranged within the 120 chute beneath the table and having toothed elements arranged to extend between the slats and engage and draw down the wool, and means for intermittently operating the reel at variable working speeds according to 125 the position of the table.

2. In a delivery mechanism for wool scouring machines, the combination, with a wool feeder, and a wool chute, of a slatted feed table within said chute, a rotary reel 130

having teeth to extend between the slats of the table and draw down the wool, means for operating the reel, and means for adjusting the table and reel with relation to 5 each other and controlling the speed of said operating means.

In testimony whereof I affix my signature in presence of two witnesses.

EDWARD P. O'BRIEN.
